Primary Examiner — Lilyana Bekic*(74) Attorney, Agent, or Firm* — Cook Alex Ltd.(57) **CLAIM**

The ornamental design for a syringe pump, as shown and described.

DESCRIPTION

FIG. 1 is a first front perspective view of a syringe pump showing our new design;

FIG. 2 is a second front perspective view thereof;

FIG. 3 is a first rear perspective view thereof;

FIG. 4 is a second rear perspective view thereof;

FIG. 5 is a front elevational view thereof;

FIG. 6 a rear elevational view thereof;

FIG. 7 is a right side elevational view thereof;

FIG. 8 is a left side elevational view thereof; and,

FIG. 9 is a top plan view thereof.

The broken lines in the drawings depict portions of the syringe pump that form no part of the claimed design.
